UNITED STATES PATENT OFFICE.

HENRY J. CHILTON, OF OAK PARK, ILLINOIS.

BOTTLE-CROWNING MACHINE.

1,324,645.

Specification of Letters Patent.

Patented Dec. 9, 1919.

Application filed November 30, 1917. Serial No. 204,522.

To all whom it may concern:

Be it known that I, HENRY J. CHILTON, a citizen of the United States, residing at Oak Park, in the county of Cook and State of Illinois, have invented certain new and useful Improvements in Bottle-Crowning Machines, of which the following is a description, reference being had to the accompanying drawings, which form a part of my specification.

The invention relates to a machine for applying metal caps or closures, such as crown corks, to bottles and the like made of glass or vitreous material.

While machines of this character are designed to crown bottles, or like receptacles, of substantially uniform length or height, the bottles often vary in height to a considerable degree, thus necessitating the employment of yielding mechanism whereby a yielding relation between the crowning mechanism and the bottles, or vice versa, may be obtained, during the continuous operation of the machine, to avoid the breaking or injury of the fragile receptacles or bottles.

At the same time it is essential to employ mechanism of such character and operation, that constant pressure will be exerted during the crowning operation regardless of variations in the sizes of the bottles or receptacles.

The object of my invention is to provide means which will control the crowning mechanism so as to keep a constant pressure on the crowns or caps during the crowning operation.

Another object of my invention is to provide means for properly centering and guiding the bottles in conjunction with the crowning mechanism, which, at the same time, will provide a clear unobstructed table-top, and will enable the table-top being kept clean during the operation of the machine and thus eliminate the possibility of any interference with the proper operation of the machine.

The purpose of my invention is to produce a machine embodying means, adapted to provide the operations and results hereinbefore mentioned, which will be simple in construction and operation, and at the same

time capable of automatic operation, at a desirable speed; the objects and advantages of the invention being readily comprehended from the following detailed description of the drawings, wherein:

Figure 1 is a sectional elevation of my improved machine.

Fig. 2 is a cross-sectional view taken on the line 2—2 of Fig. 1, looking downwardly.

Fig. 3 is a cross-sectional view taken on the line 3—3 of Fig. 1, looking upwardly.

Fig. 4 is a detail, in perspective, of the pressure controlling mechanism.

As an exemplification of my invention, the improved elements or means, capable of operations adapted to produce the effects or results hereinbefore enumerated, are shown applied to a well known type of crown or cap-applying machine provided with the usual vertical stationary post 15, which is provided with a shoulder at 16 to afford suitable support for the rotating carrier or turret 17. Suitable antifriction material interposing the lower end of the turret and the shoulder 16, is shown at 18, in order to provide a proper antifriction bearing. The lower end of the turret or carrier 17 is provided with a downwardly presented annular gear 19, maintained in proper relation with the turret by means of a set-screw 20. The annular gear 19 meshes with a bevel-gear 21 secured to the end of a power-shaft mounted in the bearing block 22; the opposite end of the power-shaft being provided with a pulley 23 to receive a suitable belt for imparting power thereto.

Concentrically arranged with the post 15, and suitably secured on the turret 17, is a sleeve-member 24 which is threaded exteriorly to enable proper adjustment of the elements mounted thereon. The sleeve-member 24 is adapted to support a suitable frame or carrier 25, which is provided with a plurality of crown or cap-applying elements shown at 26 corresponding in number with the number of bottles or receptacles adapted to be held by the centering or positioning means later to be described and mounted above the turret. The frame or carrier 25 has mounted thereon an annular gear 27 having an elongated hub portion so as to bring it up into mesh with a bevel-gear 28

which is suitably mounted on the depending stem-portion of a hopper or crown-holding receptacle 29. The stub-shaft on which bevel-gear 28 is mounted is also provided with a gear 30 meshing with a gear 31 whereby proper operation or movement is imparted to the crown or cap-feeding mechanism located in the end 32 of the hopper; the mechanism inducing the crowns or caps to be fed into the chute or guide-way 33, whereby the crowns or caps are progressively fed into the heads 34 of the cap-applying elements 26.

As the elements thus far described are of a well known construction, further specific description thereof need not be entered into, except in so far as the lower ends or head-portions 34 of the cap-applying elements 26 are concerned. With the elements 26 arranged to rotate with the table and with the simple type of crowning elements shown, it is necessary to arrange the heads in juxtaposition so that at no time will there be a hiatus at the orifice of the chute or guide-way 33, which would permit the crowns or caps to discharge onto the table to be wasted and at the same time undoubtedly empty the hopper or crown-holding receptacle 29.

In order to obviate the difficulty described, I show the head-portions 34 of the elements 26 enlarged and in the nature of sectoral blocks arranged in juxtaposition, adapted to permit independent vertical movement of each element, while at the same time constantly provide a closure for the end of the chute or guide-way 33, except for the crown-receiving groove in the heads 34; that is a segmental groove in each head which registers with the grooves in adjacent heads, as shown in dotted lines in Fig. 3; the groove in each head being inwardly recessed, as shown, to communicate with the vertical slide-way for the pressure-applying plunger in each element—see Fig. 3.

The crown-applying elements are reciprocatingly mounted and yieldingly maintained in their normal or raised positions by means of the coil-springs 35, as shown to the left in Fig. 1. The crown-applying elements 26 are each provided at their upper ends with suitable antifriction member or roller 36 which are adapted to come into contact with or be engaged by the operating mechanism or pressure-applying means which comprises my invention.

This means, in the specific construction illustrated, consists of a yoke member 37, shown in detail in Fig. 4, which is oscillatingly mounted by means of trunnions in suitable brackets or plates shown at 38, 38 in Fig. 2, and in dotted lines in Fig. 1; the brackets or plates may be in the nature of lobes formed integral with and depend from the lower end of the non-rotating hopper or receptacle 29. The member 37 is preferably

shown in the form of a yoke so as to straddle the hub of gear 27 and provide a firm bearing for the member 37. The under side of member 37 is provided with a cam-surface 39, see Fig. 4, arranged in alinement 70 with the center of travel of the cap-applying elements. The outer end of the cam-yoke 37 is pivotally connected to a sleeve 40 adjustably secured on the threaded end of an upwardly disposed rod 41. The lower end of 75 the rod 41 is pivotally secured to an arm 42 which, in turn, is pivotally secured to the casing 43 surrounding the turret and which supports the ledge or table 43a. The table, in the particular exemplification shown, is 80 provided with a suitable aperture for the passage of the rod 41. The arm 42 is adapted to carry a suitable weight or weights which are preferably shown in the form of disks 44, maintained in place, for example, 85 by means of the nuts 45, 45 which screw onto the threaded end of the arm 42. The method illustrated enables the weight on the arm to be regulated by increasing or decreasing the number of disks to provide sufficient 90 weight or pressure for the proper operation of the crown or cap-applying elements against the action of their respective springs 35.

The sleeve-member 24, at a point slightly 95 above the point where it is secured to the turret 17, is provided with a bottle-centering element 46. This centering means is preferably shown in the nature of a double star-wheel construction or hub-member provided with radially disposed fingers or spokes, with the intervening spaces or sockets of proper depth to receive a bottle or receptacle and to center the necks thereof with the apertures 47 in the heads 34 of the 100 crown applying elements 26. The centering element 46 is secured to sleeve 24 in any suitable manner, as for example by setscrew 48, so as to induce the element 46 to rotate with the sleeve and therefore also 105 with the crown-applying elements mounted in the carrier 25.

The bottles are fed into the star-wheel or between the projecting fingers 46 in any suitable manner and at a point in advance, 115 (relative to the rotation of the machine) of my improved pressure-applying mechanism, and as the machine continues operation, the crown-applying elements are progressively brought beneath the pressure-applying means, to-wit the cam-yoke 37, thereby causing the rollers 36 of the cap-applying plungers to ride along the under side of the cam-surface 39. With the cam-yoke held downwardly through the action of the 120 weight 44, it is evident that the cap-applying plungers or elements will be depressed against the action of their springs 35 and a gradual yielding pressure applied to the caps. In the event of a bottle of somewhat 125 130

greater length having been fed to the machine, whereby the downward movement of the cap-applying plunger would be arrested or limited, breakage or injury of the bottle or receptacle will be avoided by the yielding relation of the pressure-applying mechanism, to-wit the pivotal connection of cam-yoke 37 and weight-carrying arm 42; the construction being such, however, as to keep 10 a constant pressure on the caps or crowns regardless of any variations in the size or length of the bottles.

In order to maintain the pressure-applying cam-yoke 37 in proper relative position, 15 in other words, to prevent it dropping down too far when the crown-applying element has been rotated beyond the action of the cam 39, I provide a limiting member or strap 49, which may be in the nature of 20 an angle-iron bent into U-shape, or any other suitable shape, with the ends thereof bolted or otherwise secured to the sides of the hopper or receptacle 29. The upper surface of the member 49 is provided with a cushioning member or element 50 composed of rubber or other suitable material, to receive the 25 impact of the dropping yoke.

With my improved bottle centering element 46, and improved manner of applying pressure to the crown or cap-applying elements, I am enabled to obtain a smooth, 30 imperforate and unobstructed table or turret-top free from any protruding and vertically movable surfaces, thus enabling the 35 top of the rotating table or turret to be kept clean and clear of any obstruction during operation of the machine.

The elements, which have not been specifically described, are of a well known construction and operate in the usual manner 40 and form no part of my invention; and the specific construction of the invention herein illustrated may be modified in certain respects without, however, departing from the 45 spirit of my invention.

What I claim is:—

1. A machine of the class described, comprising a rotatable table, a crown-holding receptacle provided with a gravity feed 50 crown guide-way or chute, and a plurality of crown-applying elements adapted to rotate in unison with said table and to be moved toward the receptacle to be capped, the lower ends of said elements terminating 55 in enlarged head portions, with the outer perimeters of the head portions of the different elements arranged in juxtaposition with each other and with the end of said chute so as to prevent the improper discharge of the crowns therefrom.

2. A machine of the class described, comprising a rotatable table, a crown-holding receptacle, a crown guide-way or chute leading 60 downwardly therefrom, and a plurality of crown-applying elements adapted to ro-

tate in unison with said table, the lower ends of said elements terminating in enlarged sectoral heads, the heads of the different elements being arranged in abutting relation with one another and with the end 70 of said chute, and being movable relative to each other, said heads being each provided with a segmental groove, for the reception of a single crown, terminating in an inwardly disposed recess for the passage 75 of a crown.

3. A machine of the class described, comprising a rotatable table, a crown-holding receptacle provided with a gravity feed crown guide-way or chute, a plurality of 80 crown-applying elements adapted to rotate in unison with said table, the lower ends of said elements terminating in enlarged head portions whose outer perimeters are arranged in abutting relation with one another 85 and with the end of said chute so as to prevent the improper discharge of crowns therefrom, and yieldingly mounted pressure-applying means secured against rotation and having a portion thereof disposed in the 90 path of said elements, said means being adapted to force said elements downwardly into crowning engagement with the receptacle to be crowned.

4. In a capping machine, the combination 95 of capping devices and a cap feeding device arranged to feed caps to the capping devices, said capping devices being mounted to rotate and reciprocate from crown receiving to crown applying position, a member 100 having means which is stationary with respect to said member for operating the cappers to apply a cap to a receptacle, said member being yieldable and having an adjustable element acting to move said member 105 and said means toward the cappers, said means permitting said cappers to be passed beyond the same to permit said cappers to reciprocate to their cap receiving position when rotated beyond the yieldable member 110 having said means.

5. In a capping machine the combination 115 of capping devices and a cap feeding device arranged to feed caps to the capping devices, said capping devices being mounted to rotate and reciprocate from crown receiving to crown applying position, and a member having means which is stationary with respect to said member for operating the cappers to apply a cap to a receptacle, 120 said member being yieldable and having a weight, said member and said means permitting the cappers to pass beyond said yieldable member and said means to permit said cappers to move to their cap receiving 125 position when rotated beyond the yieldable member having said means.

6. In a capping machine the combination 130 of a plurality of capping devices mounted to be rotated and reciprocated from crown

4

receiving to crown applying position, means for feeding a cap to the cappers and a pivoted member having means which is movable with the pivoted member for operating the cappers to apply a cap to a receptacle, said member and said means providing means to operate the cappers to apply a cap when rotated to cap applying position, said member and said means permitting the cappers to reciprocate to crown receiving position when rotated beyond said pivoted member having said means.

7. In a capping machine the combination of a plurality of capping devices mounted to be rotated and reciprocated from crown receiving to crown applying position, a yieldable member having means movable with the yieldable member for operating the cappers to apply a cap to a receptacle, said member and said means providing the means to operate the cappers to apply a cap when rotated to cap applying position, said member and said means permitting the cappers to reciprocate to crown receiving position when rotated beyond said member having said means.

8. In a capping device the combination of a plurality of cap applying devices arranged to rotate and reciprocate from cap receiving to cap applying position, means for feeding a cap to the capping devices, and yieldable means having means movable with the yieldable means for actuating the cappers to apply a cap, said yieldable means having said means providing the means to actuate the cap applying means and said yieldable means being arranged to permit the cappers to pass the same after a cap has been applied to allow said cappers to reciprocate to their cap receiving position, and means for limiting the movement of said cappers when moved to said last named position.

9. In a capping device the combination of a plurality of cap applying devices arranged to rotate and reciprocate from cap receiving to cap applying position, means for feeding a cap to the capping devices and means having a cam which is stationary with respect to said means for actuating the cappers and to apply a cap, said first mentioned means and the cam providing the means to actuate the cap applying means, and being arranged to permit the cappers to pass said means after a cap has been applied to allow the cappers to reciprocate to their cap receiving position, and means for limiting the movement of said cappers when moved to said last named position.

10. In a capping machine the combination of a hopper, a support for the hopper, a plurality of capping devices mounted upon the support, means for feeding caps to the capping devices, means operably connected with said means for rotating the cap-

ping devices, and yieldably mounted means having means which is stationary with respect to said last mentioned means for actuating the capping devices, said last mentioned means permitting the capping devices to move into position to receive a cap from the cap feeding means when rotated beyond the yieldable means.

11. In a capping machine the combination of a hopper, a stationary shaft upon which the hopper is mounted, a plurality of capping devices constructed to rotate about said shaft, and means for actuating the cappers, said means being yieldable and carried by the hopper, and carrying means, which is stationary with respect to the yieldable means for actuating the cappers to apply a cap, said yieldable means and the means which it carries permitting the cappers to reciprocate to cap receiving position when rotated beyond the yieldable means and the means which it carries.

12. In a capping machine the combination of a capping device mounted to rotate and reciprocate from crown receiving to crown applying position, a cap feeding device arranged to feed caps to the capping device during the rotation of the capping device, a yieldable member having means movable therewith for operating the capper to apply a cap to a receptacle, said means permitting the capper to be passed beyond the same after a cap has been applied, and the member which carries the means permitting the capper to be moved beyond it to allow the capper to reciprocate to its cap receiving position.

13. In a capping machine the combination of a capping device, means for feeding caps to the capping device and means for actuating the capping device, said capping device being mounted to rotate from the cap feeding device to the means for actuating the capping device, the capping device being also mounted to reciprocate when actuated by the means for actuating the same, means for restoring the capping device to cap receiving position when moved beyond the means for actuating the capping device, the means for actuating the capping device including a yieldably mounted member having means stationarily mounted with respect to said member, and means for moving said member toward the capping devices.

14. In a capping machine the combination of capping devices and cap feeding means arranged to feed caps to the capping devices, means provided to actuate the capping devices, said capping devices being mounted to rotate from the feeding device to capping position, yieldable means having a weight to actuate the cappers, said cappers being mounted to reciprocate to apply a cap when actuated by the yieldable means having the weight and to return to cap receiving posi-

tion when moved beyond the yieldable means, said cappers having means to receive a cap and means movable with the cappers to control the cap feeding means to prevent the improper discharge of said caps.

15. A machine of the class described, comprising a crown holding receptacle having a crown guideway or chute, and a plurality of crown applying elements arranged to be moved toward the receptacle to be capped, one end of said crown applying elements having portions which are arranged in juxtaposition with each other and having means to receive a crown and to prevent the improper discharge of the crowns from the chute.

16. In a capping machine the combination of capping devices and cap feeding means arranged to feed caps to the capping devices, means provided to actuate the capping devices, said capping devices being mounted to rotate from the cap feeding device to the means for actuating the capping devices, each capping device having a portion which is movable relatively to a similar portion of another capping device into which caps are fed from the cap feeding means and having means which closes the cap feeding means to prevent a cap from being improperly discharged from the feeding means during rotation.

17. In a capping machine the combination of a cap feeding device, a plurality of capping elements and means for actuating the capping elements, the capping elements having portions into which caps are fed when said elements are moved into alignment with the feeding device, and having means movable horizontally and transversely with relation to the feeding device, said means preventing the feeding of caps when other capping elements are moved beyond the cap feeding device.

18. In a capping machine the combination of a cap feeding device, a plurality of capping elements and means for actuating the capping elements, said capping elements being movable to successively receive a cap from the feeding means, and said capping elements having vertically movable means extending from one to the other for controlling the feeding of said caps, as the capping elements are successively moved into alignment with the cap feeding device.

19. In a capping machine the combination of a cap feeding device, a plurality of capping elements having means to receive a cap from the cap feeding means, and means for actuating the capping elements, said capping elements being movable to successively receive a cap from the feeding means and said capping elements having means extending from one to the other for controlling the feeding of said caps as the capping elements

are successively moved into alignment with the cap feeding device, said first mentioned means and the means which extends from one to the other for controlling the feeding of said caps registering with each other, the means for actuating the capping elements causing the capping elements to be successively moved out of registration with each other, and the last mentioned means permitting said cappers to be again moved into registration with the cappers arranged between the actuating means and cap feeding means after said cappers have been moved beyond the means for actuating the cappers.

20. In a capping machine the combination of capping devices and cap feeding means arranged to feed caps to the capping devices, means provided to actuate the capping devices, said capping devices being mounted to move from the cap feeding device to the means for actuating the capping devices, each capping device having a portion which is movable relatively to a similar portion of another capping device into which caps are fed from the cap feeding means and having means which closes the cap feeding means to prevent a cap from being improperly discharged from the feeding means.

21. In a capping machine the combination of a plurality of capping devices, means for feeding caps to the capping devices, and means for actuating the capping devices, the capping devices being movable from the cap feeding device to the means for actuating the capping devices, said capping devices having means into which caps are fed and retained as same are fed from the feeding means, and having means for preventing the improper discharge of caps from the feeding means, said last mentioned means being movable with respect to similar portions of another capping device.

22. In a capping machine the combination of capping devices and cap feeding means arranged to feed caps to the capping devices, means for actuating the capping devices, the capping devices being movable from cap receiving to cap applying position and movable to apply a cap, each of said capping devices having means which are movable with the capping devices for receiving a cap and means for preventing the improper discharge of the caps from the feeding means when a cap is applied, the means for receiving a cap including a recess and the last mentioned means including a groove which cooperates with the cap feeding means.

23. In a capping machine the combination of a cap feeding device, a plurality of capping devices and means for actuating the capping devices, the capping devices being movable from cap feeding device to the means for actuating the capping devices, said capping devices having means into

which caps are fed from the feeding means and to prevent a cap from being improperly discharged from the feeding means, said means being movable with respect to similar portions of another capping device.

24. In a capping machine the combination of a plurality of cappers, cap feeding means and means for actuating the cappers, said cappers having means for receiving a cap and controlling the feeding of caps from the feeding means, said means of one capper being normally in alinement with similar means of the other cappers and being movable out of alinement therewith when actuated by the means for actuating the same.

25. In a capping machine the combination of a plurality of cappers, cap feeding means and means for actuating the cappers, each of said cappers having means for receiving a cap and controlling the feeding of caps from the feeding means, said means of each capper including a groove which registers with the groove of other cappers, and which is movable out of alinement therewith when actuated by the means for actuating the same.

26. In a capping machine the combination of a plurality of cappers, cap feeding means and means for actuating the cappers, each of said cappers having means movable with the cappers for receiving a cap and controlling the feeding of caps from the feeding means, the means for controlling the feeding of caps normally registering with similar means of other cappers and being movable out of alinement therewith when actuated by the means for actuating the cappers.

27. In a capping machine the combination of a plurality of cappers, cap feeding means and means for actuating the cappers to apply a cap, each of said cappers having means movable with the cappers when actuated to apply a cap for controlling the feeding of caps from the feeding means said controlling means of one capper normally registering with similar means of other cappers and providing a continuous closure for the cap feeding means which is permitted to intermittently feed caps to the cappers.

28. In a capping machine the combination of a plurality of cappers, cap feeding means and means for actuating the cappers, each of said cappers having means movable with the cappers when actuated to apply a cap for controlling the feeding of caps from the feeding means, said controlling means including means for intermittently permitting a cap to be fed to the cappers and preventing the feeding of caps when the cappers are moved into cap receiving position, said means consisting of a groove controlling the feeding means, and a recess into which the

caps are deposited, said groove being continuous and only broken when one of the cappers is moved to apply a cap.

29. In a capping machine the combination of a plurality of cappers, cap feeding means, means for actuating the cappers to receive a cap, and means to actuate the cappers to apply a cap, each of said cappers having means movable with the cappers when actuated by the capper actuating means for controlling the feeding of caps from the feeding means, said controlling means including means for intermittently permitting a cap to be fed to the cappers and preventing the feeding of caps when the cappers are moved into cap receiving position.

30. In a capping machine the combination of a plurality of cappers, cap feeding means, and means for actuating the cappers to apply a cap, each of said cappers having a groove and a recess, the groove of one capper alining with the groove of another capper and forming a continuous groove from one capper to the next, said groove cooperating with the feeding means to prevent the improper feeding of caps therefrom, said cappers being movable to intermittently feed caps into the recesses of each capper and the portion of the capper having the groove and recess being movable with the capper when same is actuated by the means for actuating the cap applying means.

31. In a capping machine the combination of a plurality of cappers, cap feeding means and means for actuating the cappers to apply a cap, each of said cappers having a groove and a recess, the groove of one capper alining with the groove of another capper, and forming a continuous groove from one capper to the next, said groove cooperating with the feeding means to prevent the improper feeding of caps therefrom, said cappers being movable to intermittently feed caps into the recesses of each capper and the portion of the capper having the groove and recess being movable with the cappers and out of alinement with similar portions of other cappers when the same is actuated by the means for actuating the cap applying means, and said portions being movable to permit same to move into alinement when released by the means for actuating the cappers.

32. In a capping machine the combination of a capping device, cap feeding means and means for actuating the capper, said capper having means for receiving a cap and means for controlling the improper discharge of a cap from the feeding means, said means being movable with the capper when same is actuated and said capper being movable from the feeding means to the means for actuating said capper.

33. In a capping machine the combination

of capping devices and cap feeding means arranged to feed caps to the capping devices, means provided to actuate the capping devices, said capping devices being

- 5 mounted to rotate from the cap feeding device to the means for actuating the same, each capping device having a portion which is movable relatively to similar portions of other capping devices into which
10 caps are fed from the cap feeding means and having means to prevent the improper discharge of caps from the feeding means.

34. In a capping machine the combination of capping devices, cap feeding means
15 arranged to feed caps to the capping devices and means for actuating the capping devices, said means including a yieldable member having a member stationarily arranged with respect to the yieldable member, said capping devices being mounted to move from the feeding means to capping position, and said cappers being arranged to reciprocate to apply a cap when actuated by the means for actuating the cappers and said cappers
20 having means to receive a cap and to prevent the improper discharge of caps from the feeding means.

35. In a capping machine the combination of a rotary frame, cappers carried by the
25 frame, means for feeding caps to the cappers and means movable with the frame and

relatively thereto for preventing the improper discharge of caps from the feeding means during rotation of the frame.

36. In a capping machine the combination 35 of a movable frame, capping devices and cap feeding means for feeding caps to the capping devices, and means movable with the frame and relatively thereto for preventing the improper discharge of caps from 40 the feeding means.

37. In a capping machine the combination of a movable frame, capping devices and cap feeding means for successively feeding caps to the capping devices and means movable with the frame and relatively thereto 45 for preventing the improper discharge of caps from the feeding means.

38. In a capping machine the combination of a movable frame, capping devices and cap feeding means for intermittently feeding caps to the capping devices, the capping devices being movable to successively receive a cap from the feeding means and also movable to apply a cap, and means movable with 55 the frame for preventing the improper discharge of caps from the feeding means.

HENRY J. CHILTON.
